UNITED STATES PATENT OFFICE

160,683

TELEVISION CABINET

Samuel E. Adler, Chicago, Ill.

Application February 11, 1950, Serial No. 7,903

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet of which the following is a specification, reference being had to the accompanying drawings, forming part thereof.

Fig. 1 is a front elevational view of a television cabinet, showing my new design;

Fig. 2 is a fragmentary, vertical sectional view taken on line 2—2 of Fig. 1.

Fig. 3 is a side elevational view; and

Fig. 4 is a fragmentary horizontal sectional view taken on line 4—4 of Fig. 1.

The dominant features of my design reside in that part shown in full lines on the drawings.

I claim:

The ornamental design for a television cabinet, as shown and described.

SAMUEL E. ADLER.
